UNITED STATES PATENT OFFICE.

EDGAR THOMAS HAUN, OF GILROY, CALIFORNIA.

BOWLDER GRABBER.

Application filed January 13, 1921. Serial No. 436,962.

To all whom it may concern:

Be it known that I, EDGAR T. HAUN, a citizen of the United States, residing at Gilroy, in the county of Santa Clara and State 5 of California, have invented certain new and useful Improvements in Bowlder Grabbers, of which the following is a specification.

This invention relates to grapples and the primary object of the invention is to provide 10 an improved grapple particularly adaptable for use in placer mining and which is so constructed as to remove bowlders from banks, without disturbing the gravel, so that the mining of the mineral in the gravel will 15 be facilitated.

Another object of the invention is to provide a grapple embodying a pair of pivoted jaws or sections having an improved automatic means for opening and closing the 20 same during the lowering and raising movement of the grapple and an improved means for forcibly closing the jaws or sections independent of the means for closing the same during the raising movement of the grapple, 25 so as to insure the grabbing of the bowlders by the jaws and the displacement thereof from the jaws.

A further object of the invention is to provide an improved means for constructing the 30 jaws or sections of the grapple so as to provide a strong and rigid construction and a positive means for grappling the bowlders, the jaws being also connected together in a novel manner.

A still further object of the invention is to provide a grapple of the above character which will be durable and efficient in use, one that will be simple and easy to manufacture, and one which can be placed upon 40 the market at a reasonable cost.

With these and other objects in view, the invention consists in the novel construction, arrangement and formation of parts as will be hereinafter more specifically described, 45 claimed and illustrated in the accompanying drawings, forming a part of this specification, in which:

Figure 1 is an end elevation of the improved grapple, showing the jaws thereof in 50 their closed grasping position.

Figure 2 is a similar view illustrating the jaws in their open position.

Figure 3 is a side elevation of the improved grapple showing the jaws in their 55 closed position, and

Figure 4 is a fragmentary detail vertical

sectional view through a portion of the grapple illustrating the means for forcibly moving the jaws to their closed position for grasping the bowlders.

Referring to the drawings in detail, wherein similar reference characters designate corresponding parts throughout the several views, the letter A indicates the improved grapple or bowlder grabber, which 60 includes the jaws or sections 5 and 6. The jaws 5 and 6 are formed relatively wide and each includes a plurality of tongs or arms 7 arranged in spaced relation. These arms or tongs 7 are formed of structural iron or steel 65 of the T or I-beam type and include the straight body portion 8 and the inwardly extending arcuate prongs 9. I-beam braces 10 are provided for connecting the arms or tongs together, and these I-beams are secured 70 to the inner surface of the arms as clearly shown in Figures 1 and 2 of the drawings. I-beam sections 11 are also provided for the arcuate prongs 9 of the tongs, so as to prevent lateral movement or distortion thereof. 75

The arms of the sections or jaws 5 and 6 are so arranged that when the sections are in operative relation to each other, the arms or tongs will be out of alignment with each other. This construction permits the section 80 to be swung to such a position where the arcuate portions or prongs 9 of the tongs or arms 7 will overlap. The upper inner terminals of the arms or tongs 7 of the sections 5 and 6 are provided with longitudinally 85 aligned bearing brackets 12, which receive the longitudinally extending shaft 13 which forms the pivot for pivotally connecting the sections together.

A means B is provided for automatically 90 opening the sections 5 and 6 during the lowering movement of the grapple and a means C is provided for automatically closing and for holding the sections closed during the raising movement thereof.

The means B includes a transversely extending travelling beam 15. The beam 15 may also be of I-beam construction and is arranged between the arms or tongs 7 of the sections 5 and 6 and is of a sufficient 100 length to project beyond the outer faces thereof. Relatively short pulling ropes 16 are connected to the terminals of the beam 15 and to the arms or tongues 7 adjacent the arcuate portions thereof as at 17. Cables 18 and 19 are provided for each of the 105 jaws or sections 5 and 6 and the upper ter-

minals of the cables are connected to a ring 20. The lower ends of the cables 18 and 19 are trained around respectively a pair of spaced pulley wheels 21 and 22 which are arranged on opposite sides of the transverse center of the beam 15. The inner ends of the cables 18 and 19 are connected respectively to the sections 5 and 6 adjacent to the upper inner ends thereof. These terminals 10 of the cables are secured to the upper I beams 10 which are utilized for bracing and connecting the arms or tongs 7 together.

The ring 20 has connected thereto in any preferred manner the usual hoisting cable 25, and it can be seen that when the hoisting cable 25 is utilized for supporting the weight of the grapple, the beam 15 will be raised through the medium of the cable 18 and 19 owing to the manner in which the cables are trained around pairs of pulleys 21 and 22 and connected to the sections 5 and 6. When the beam 15 is raised, the relatively short ropes 16 will pull up on the sections at the arcuate portions 9 of the 25 tongs or arms 7 thereof. This will effectively spread or open the jaws or sections.

The means C utilized for bringing the jaws or sections 5 and 6 together when the grapple is being raised consists of cables 30 and 31 which have their upper terminals connected to a common ring 32. These cables 30 and 31 are provided respectively for the sections 5 and 6. The cable 30 is trained around a pulley 33 carried by the section 5 and then around a pulley 34 carried by the section 6 adjacent to the arcuate portion or prongs thereof. The cable is then extended across the grapple and secured as at 35 to the section 5 adjacent to its arcuate portion 9.

The cable 31 is trained around a pulley 36 carried by the section 6 adjacent to its upper end and then around a pulley 37 carried by the section 5 adjacent to its lower end and is secured as at 38 to the section 6 adjacent to its lower end. A suitable hoisting cable 39 is secured to the ring 32 and it can be seen that when the grapple is raised by the cable 39 the two jaws or sections 5 and 6 will be brought toward each other owing to the manner in which the cables 30 and 31 are trained around the pulleys 33, 36, 34 and 37.

A means D is provided for forcibly bringing the jaws or sections 5 and 6 together for insuring the engagement of the bowlders by the jaws, and this means D includes a cylinder 40 which is bolted or otherwise secured as at 41 to the section 5 adjacent to its upper end. This cylinder 40 has reciprocably mounted therein a piston 42 and the piston rod 43 thereof is provided with a guide pulley 44. A cable 45 is trained around the guide pulley 44 and has one end secured to a bracket 46 carried by the section

5 adjacent to its lower end. The cable after leaving the pulley 44 is trained around a pulley 47 carried by the section 5 adjacent to its lower end and is then brought over to the sections and secured thereto as at 48 70 adjacent to its lower end.

The lower end of the cylinder 40 is provided with an inlet opening 49 which has communicating therewith a feed pipe 50. It can be seen that when pressure is admitted into the cylinder through the inlet 49, the piston 42 will be forced to the upper end of the cylinder, thus drawing the piston rod 43 inwardly. This will pull up on the cable 45 and thus draw the jaws or sections 80 5 and 6 forcibly together.

In operation of the improved grapple the same is lowered by means of the cable 25 which will draw up on the beam 15 and open the jaws or sections 5 and 6 and position the prongs or arcuate portion 9 of the tongs or arms 7 thereof in a boulder grasping position. The grapple is then lowered over the desired place and the cable 39 may be then raised a short distance for bringing 90 the jaws 5 and 6 toward each other. Pressure is then admitted into the cylinder 40 which will forcibly bring the sections together and force the bowlders on the arcuate portions or prongs 9 thereof. The grapple is then raised by the cable 39 which will hold the jaws or sections 5 and 6 in their closed position and thus prevent the dropping of the bowlders therefrom.

From the foregoing description, it can be 100 seen that an improved and simple grapple for bowlders has been provided, which is of exceptionally durable and rigid construction and which is so constructed that the jaws will be automatically moved toward 105 and away from each other, when the device is being raised or lowered.

Changes in details may be made without departing from the spirit or scope of this invention; but,

I claim:

1. A grapple comprising a pair of pivotally connected sections, means for automatically opening and closing the sections during the lowering and raising thereof, and means independent of the first mentioned means for closing the sections.

2. A grapple comprising a pair of pivotally connected sections, lowering and hoisting cables for the sections, means operated by said cables for automatically opening and closing the sections during the lowering and raising thereof by said cables, and independent means for moving said sections independent of said cables.

3. A grapple comprising a pair of sections, means pivotally connecting the sections together at their upper ends, a cylinder carried by one of the sections, a piston reciprocably mounted in said cylinder, a pulley car-

ried by said piston, a cable, means securing one end of the cable to the section carrying said piston, a guide pulley carried by said section, means securing the opposite ends of the cable to the other section, the cable being trained around said pulleys.

4. In a grapple, a pair of sections, means hingedly connecting the sections together, lowering and raising means for the sections, 10 a cylinder carried by one of the sections, a piston reciprocably mounted in said cylinder, means for feeding fluid to the cylinder, a guide pulley carried by the piston, a guide pulley secured to the section carrying the cylinder and arranged below the same, means for admitting fluid pressure to the cylinder, a cable trained around the pulley, and means securing the terminals of the cable to the sections.

20 5. A grapple comprising a pair of hingedly connected sections, a hoisting and a lowering cable, a travelling beam carried by the sections and arranged to project beyond the outer sides thereof, guide pulleys carried 25 by the beam, means connecting the opposite ends of the beams to the sections adjacent to their lower ends, a pair of cables, means connecting the upper ends of the cables to the lowering cable, said last mentioned 30 cables being trained around the guide pulleys, and means securing the inner ends of the cables to the sections.

6. A grapple comprising a pair of sections, means hingedly connecting the sections together at their upper ends, a hoisting and a lowering cable, upper and lower guide pulleys carried by the inner surface of the sections, cables trained around one pulley carried by one section and around one 40 pulley carried by the opposite section, means securing the inner ends of the cables to the sections adjacent to their lower ends, and means connecting the upper ends of the cables to the hoisting cable.

45 7. A grapple comprising a pair of pivotally connected sections, a hoising and a

lowering cable, upper and lower guide pulleys hingedly carried by the inner surface of each section, cables trained around one guide pulley of one section, and around one 50 pulley of the other section, means securing the inner ends of the cables to the sections, means securing the outer ends of the cables to the hoisting cable, a travelling beam, pairs of guide pulleys carried by the travelling beam, cables carried by said beam pulleys, means securing the inner ends of the cables to the sections adjacent to their upper ends, means securing the outer ends of the last mentioned cable to the lowering 60 cable, and means securing the outer ends of the beam to the sections adjacent to the lower ends.

8. A grapple comprising a pair of pivotally connected sections, a hoisting and a 65 lowering cable, upper and lower guide pulleys hingedly carried by the inner surface of each section, cables trained around one guide pulley of one section and around one pulley of the other section, means securing the 70 inner ends of the cables to the sections, means securing the outer ends of the cables to the hoisting cable, a travelling beam, pairs of guide pulleys carried by the travelling beam, cables carried by said beam 75 pulleys, means securing the inner ends of the cables to the sections adjacent to their upper ends, means securing the outer ends of the last mentioned cables to the lowering cable, means securing the outer ends of the beam to the sections adjacent to their lower ends, a cylinder carried by one of the sections, a plunger reciprocably mounted in the cylinder, a guide pulley carried by the plunger, a guide pulley carried by the section 80 supporting said cylinder, a cable trained around said last mentioned pulley, means connecting the opposite terminals of the last mentioned cable to the sections, and means for admitting fluid pressure to the cylinder. 85 90

EDGAR THOMAS HAUN.
